FIRE EXTINGUISHER

Filed Feb. 18, 1924

William R. Walker INVENTOR

BY
Jeffrey Leibman, Esq.,
ATTORNEY

UNITED STATES PATENT OFFICE.

WILLIAM W. WALKER, OF PHILADELPHIA, PENNSYLVANIA, ASSIGNOR, BY MESNE ASSIGNMENTS, TO AMERICAN LA FRANCE AND FOAMITE CORPORATION, A CORPORATION OF NEW YORK.

FIRE EXTINGUISHER.

Application filed February 18, 1924. Serial No. 693,486.

The invention relates to portable foam-type fire extinguishers and the like, and its object is to prevent or reduce the tendency toward the formation of deposit or crust on 5 or adjacent to the stopple seat of the inner receptacle such as might impair the reliability of the extinguisher by causing the stopple to stick to the seat and thus prevent or retard the mixture of the solutions. The 10 invention may be used alone for this purpose, but in the interest of caution is desirably supplemented in practice by additional means also designed to insure free and prompt stopple opening. The object 15 of the invention also comprehends a simplification of the cage structure and of its means of junction with the inner container, enabling the same to be manufactured at low cost while providing ample interior 20 space for the movement of the stopple and discharge of solution, these being advantages independent of the seat-protecting function first mentioned, although both combine to afford an improvement in the 25 art.

In the accompanying drawing, Figure 1 is a vertical central section partly broken out of a conventional foam-type fire extinguisher having the invention in preferred 30 form applied to it.

Figure 2 is an enlarged axial cross-section through the stopple seat of Figure 1.

Fig. 3 is a section on line III—III of Fig. 2.

The main or outer receptacle marked 1 is provided with the usual spout outlet for the foam and the usual cover cap screwed to the neck portion. The inner receptacle, which in this case is removable through the 35 neck, is formed of flat sheet metal, rolled and seamed to form a tubular container body 2, and closed at its lower end by which it is seated on the bottom of the main receptacle. Its upper end is normally closed 40 by a stopple 3 resting on the stopple seat 4 and around and above the seat, it is provided with a cage structure 5 the function of which is to support the inner receptacle in the neck opening of the main receptacle laterally or vertically, or both, and 45 to provide a cage space for confining or guiding the stopple.

It will be understood that when the extinguisher is to be used, it is tipped or inverted

and the stopple is removed from its seat 55 so as to allow the solution of the inner receptacle, the acid solution, to flow through the cage ports into contact with the basic solution in the outer receptacle, thereby generating the foam for discharge through 60 the hose outlet. The stopple falls away from its seat in some types of extinguishers and in others it is withdrawn manually as by the operation of a screw extending to the exterior. In either case the principles of 65 this invention can be applied with advantage, but the deposit-preventing means is specially useful for the gravity-operated stopple. The acid solution is commonly 70 sulfate of aluminum, and the basic, sodium bicarbonate containing licorice, or the like, as the foaming agent.

In accordance with this invention the cage structure 5 is formed of flat sheet metal rolled into cylindrical form with its edges 75 lapped and soldered or riveted, or both, forming a cylinder of somewhat greater diameter than the tube 2 and of sufficient length to extend from near the main cover cap downwardly to a point somewhat below 80 the stopple seat or the upper end of the receptacle and above the normal liquid level in the outer receptacle. It is secured to the inner receptacle, in the present case, by means of the same part which forms the 85 stopple seat, this being a simple annular stamping secured by its middle 6 to the top edge of the tube 2 and projecting upwardly therefrom to form the seat 4 which is preferably bevelled or sharpened, in accordance 90 with the invention of patent No. 1,296,993, to guard against stopple sticking. The lower end of this junction piece extends downwardly and outwardly, away from the wall of the inner receptacle where it is soldered or otherwise secured to the bottom of the cage cylinder 5.

By this arrangement a rigid connection is established and a downwardly directed edge 7 is formed at the base of the cage, 100 separated from the inner receptacle by an annular space, marked 8, which extends upwardly between the cage wall and the inner receptacle and is closed at its top. The effect of this construction is to produce a 105 considerable extent of surface intervening between the outer liquid level and the stopple seat, thereby establishing an increased

distance over which the liquid in the outer receptacle must creep in order to reach the seat, where, by evaporation, it is likely to form a deposit causing the stopple to stick closed. It has been explained that creeping is an effect of capillarity, the liquid tending to flow into the minute crevices between the microscopic crystals that have been produced by previous wetting, thus gradually building up further crystals and advancing the deposit toward the seat. The process is a slow one and increase in the length of the creep-path is correspondingly effective to prevent deposit on the seat. Any exterior configuration of the inner receptacle, above the liquid level in the outer container, which will thus increase the creep-path, will obviously have a similar effect and will, to that extent, be the equivalent of the means just described and within this invention. The reentrant surface formed by the open-bottom chamber 8 is believed to be the most convenient means of increasing the distance. By the described construction, moreover, the stopple seat is also protected against being wetted by splashing of the outer solution, by virtue of the ledge formation resulting from the difference in diameter of the tube 2 and the cage cylinder. The splash is caught in the chamber 8 and flows back on the tube wall or drips off of the edge 7 with the least tendency to reach the stopple seat. Obviously, however, this splash-guard effect can also be produced by other constructions or configurations of the inner receptacle, whether the cage is united direct to the tube 2 or united thereto by means of a junction piece such as that shown and all such ledge formations will have the effect of increasing the creep-path whether they contain the reentrant, closed top chamber, such as 8, or not. In its preferred form the protection of the seat is obtained by the ledge formed by the chamber and drip edge, which parts serve both as a splash guard and as a means of increasing the creep-path.

When the cage structure is made of thin stock, it may if desired be suitably reinforced, at its extreme upper end, by flanging or beading. The port openings can be punched in the sheet stock before it is rolled up to make the cage cylinder and such ports desirably extend below the top of the tube 2 and the part 6, in order that any liquid striking the seat may completely drain away from it and fall off the drip edge. The simplicity of the cage structure will be obvious. The vertical dimension of the annular splash chamber 8 may be increased with advantage because this increases the length of the creep-path. The splash-guard and the extended creep-path combine effectively with the narrow or knife-edge stopple seat since if the deposit eventually reaches the seat, after a long lapse of time, its forma-

tion thereon is so thin that firm adhesion between the stopple and such an edge is practically impossible.

I claim:

1. A foam-type fire-extinguisher comprising an outer solution-containing receptacle, an inner receptacle removably contained therein, the latter having a stopple seat and a ledge formation projecting outwardly from the wall of the inner receptacle above the liquid level in the outer receptacle, and serving jointly as a splash guard and as means for increasing the creep-path between the outer solution and the seat. 70

2. A fire extinguisher comprising outer and inner solution-containing receptacles, the latter having a stopple seat and being provided with a downwardly directed drip edge intervening between the solution level of the outer receptacle and the stopple seat. 85

3. A fire extinguisher comprising outer and inner solution-containing receptacles, the latter having a stopple seat and being provided with a downwardly directed drip edge and an annular closed top chamber both intervening between the solution level of the outer receptacle and said seat. 90

4. A fire extinguisher comprising outer and inner solution-containing receptacles, the latter having a stopple seat and provided with a downwardly open, closed top annular chamber intervening between the same and the solution level in the outer receptacle. 95

5. A fire extinguisher containing an inner receptacle comprising a tubular body having 100 a stopple seat in combination with a cage structure providing a drip edge surrounding said tubular body and spaced therefrom.

6. A fire extinguisher containing an inner receptacle comprising a tubular body, a 105 cage structure, and a separately made junction piece uniting said parts and constituting a stopple seat.

7. A fire extinguisher containing an inner receptacle having a cage structure of greater 110 diameter than itself and a separately made annular junction piece securing said structure to the receptacle in spaced relation thereto.

8. A fire extinguisher containing an inner 115 receptacle comprising a tubular body, a cage of greater diameter than said body and a junction piece secured by its middle zone to said body, the upper end of said piece serving as a stopple seat and the lower end 120 being secured to the lower part of said cage.

9. A fire extinguisher containing an inner receptacle comprising a tubular body, a sheet metal cage and an intermediate, separately made, sheet metal junction piece between said parts serving as a stopple seat. 125

10. A fire extinguisher having a main receptacle containing an inner receptacle, the latter comprising a tubular body seated by its end in the main receptacle and having a 130

sheet metal cage of greater diameter than the tubular body occupying the neck opening of said main receptacle and an annular sheet metal wall connecting the lower end of the 5 cage with the upper end of said tubular body.

11. A foam-type fire extinguisher comprising an outer solution-containing receptacle having a filling opening and cap, an 10 inner tubular receptacle laterally and removably supported in said filling opening and having a stopple seat and also provided

with a radially projecting ledge above the solution level in the outer container and below said stopple seat, serving to increase 15 the creep-path.

12. A foam-type fire extinguisher containing an inner receptacle comprising a tubular body, a cage structure and junction piece between them, the upper edge of said 20 piece forming a thin stopple seat.

In testimony whereof, I have signed this specification.

WILLIAM W. WALKER.
